COMBINED SPICE RACK AND BOTTLES THEREFOR

Reiner Lubge, New York, N.Y., assignor to Lubalin,
Smith, Carnase, Inc., New York, N.Y.

Filed July 25, 1972, Ser. No. 275,000

Term of patent 14 years

Int. Cl. D6—04; D7—02

U.S. Cl. D7—71

Fig. 1.

Fig. 2.

Fig. 3.

Fig. 4.

FIG. 5.

FIG. 6.

FIG. 1 is a front perspective view of a combined spice rack and bottles therefor showing my new design;

FIG. 2 is a side view thereof;

FIG. 3 is a top view thereof;

FIG. 4 is a rear view thereof;

FIG. 5 is a front perspective view of the combined spice rack and bottles therefor, with the bottles shown removed, in order to show more clearly the configuration of the rack; and

FIG. 6 is a front perspective view of another embodiment of my design, with the bottles shown removed, in order to show more clearly the configuration of the rack.

I claim:

The ornamental design for a combined spice rack and bottles therefor, substantially as shown and described.
